UNITED STATES PATENT OFFICE.

ADDISON A. CARDWELL, OF RYE, NEW YORK.

MEANS FOR HUMIDIFYING ARTIFICIALLY-HEATED AIR.

1,117,785.

Specification of Letters Patent.

Patented Nov. 17, 1914.

Application filed March 23, 1914. Serial No. 826,517.

To all whom it may concern:

Be it known that I, ADDISON A. CARDWELL, a citizen of the United States, and a resident of Rye, county of Westchester, and 5 State of New York, have invented certain new and useful Improvements in Means for Humidifying Artificially-Heated Air, of which the following is a specification.

My improvements relate to humidifying 10 appliances and are designed primarily to adapt to steam or hot water radiators, my system of compensating for lack of moisture in artificially heated air by utilizing the heating means to supply, in whole or in 15 part, the deficiency otherwise created thereby, as in my concurrent applications No. 820,404, filed Feb. 24th, 1914, and No. 825,036, filed Mar. 16th, 1914.

To this end the present invention consists 20 more particularly in the specific construction and arrangement of parts described and claimed herein.

The absorbent medium is supported by a 25 conduit and arranged to be moistened by the fluids issuing therefrom and exposed to the atmosphere and to the heat from the radiator and so formed as to offer substantially no resistance to the fluids issuing from said conduit.

30 In the accompanying drawings, Figure 1, represents an end view of the top portion of a hot water radiator provided with means for utilizing hot water from the radiator for the purpose of humidifying the air heated by said radiator; Fig. 2, is a top view of the parts shown in Fig. 1; Fig. 3, a side elevation thereof; Figs. 4, 5, and 6, are views like unto the first three figures, showing the application of my humidifying means to a 35 steam radiator; Fig. 7, is a top view of the fluid vent or escape valve which is interposed in the conduit between the radiator and the evaporator; Fig. 8, is a central longitudinal sectional elevation of the same;

40 Fig. 9, is a sectional elevation of the reservoir for volatiles, and the evaporator, the latter broken away in part. Fig. 10, is a 45 sectional detail of a modification of the evaporator.

50 The main object of the invention is the utilization of the heating fluid as a humidifying agent to render the air heated by the radiator less deleterious to health and comfort.—to counteract in fact the evil effects 55 of overheating and dryness produced in the surrounding air by direct convection and

radiation from the surface of the radiator. And for this purpose the usual air vents may be utilized, my humidifying appliance performing also the function of the ordinary air vent provided in both hot water and steam radiators. Thus in the first three figures in the drawings, which include the symbolical representation of the upper part of an end loop R, of a hot water radiator, 60 the usual top or high tap r, provided for the usual air vent, is used as a means of attachment for my valve casing V, whereas in the succeeding three figures R', represents the end member of a steam radiator, and in like manner the usual low tap r', provided for the customary air vent, is utilized to make connection with the valve casing V. By preference a screw needle valve n, is mounted in the casing V, controlling the 75 available area of the vent duct c, as shown in Fig. 8, although any form of valve may be substituted, if so desired. The outer end of the valve stem may be flattened or angular in cross section to afford means for engagement with a wrench or turning implement, or an index pointer p, attached to the valve stem may be utilized as a handle,—a concentric index i, on the casing V, being provided for use in conjunction with the 80 pointer p, to assist in setting and regulating the flow.

Interposed between the connection with the radiator loop R, or R', I prefer to use a filter chamber F, containing a filtering 90 medium f, adapted to eliminate from the out-flow from the radiator any sedimentary or foreign matter that may be carried over by the fluid pressure, so that only pure water or moist vapor escapes through the 95 vent v, to the absorbent evaporative medium m. This filter is preferably placed between the radiator and the vent v, as shown in the drawings, particularly Fig. 8, in which the casing for the filter is attached directly to 100 the valve casing V, the filtering material being held in place between arched foraminous partitions f', f''.

The absorbent evaporative medium m, may obviously be arranged and supported 105 in various ways without departing from the spirit and intent of my invention in this respect, provided it is arranged in juxtaposition to the radiator so that the heat emanating therefrom will insure the vaporization of the moisture absorbed by the material m. An effective arrangement is to po-

sition the absorbent evaporative material m , longitudinally (as related to the length of the whole radiator) within the central spaces r^2 , between the vertical members of 5 the loops, as indicated in the drawings, this arrangement affording a maximum of heat for evaporative purposes while isolating and protecting the evaporative device. The latter may consist simply of a conduit pipe 10 c , communicating with the vent port v^2 , in the valve casing V , the other end of said conduit c , being connected with a foraminous tube or cylinder t , (Fig. 9) preferably of non-corrosive material, in which the absorbent evaporative medium m , is positioned; or any other equivalent means of 15 supporting said absorbent evaporative medium and presenting within the heating area of the radiator (the nearer the latter the better without actual contact therewith) may be substituted; as may also other means of moistening the evaporative medium m , with moisture obtained from the radiator itself,—the utilization of the heating fluid 20 for this purpose being the essential feature in this respect. In the modification shown in Fig. 10, the evaporative medium m , consists of a cloth or textile fabric hung over the conduit c , which is perforated to allow 25 the moisture to drip into said pendent evaporative medium.

Since the heating fluid, whether hot water or steam, is apt to contain elements that impart a disagreeable odor to the atmosphere 30 when liberated therein, I connect the conduit c , with a reservoir a , for volatile material a' , the emanations from which pass through a duct a^2 , into said conduit c , as illustrated more particularly in Fig. 9. Thus the fluid 35 fed to the absorbent evaporative medium m , may be impregnated automatically with a deodorant, disinfectant, perfumery or medicament, as may be found most expedi-

ent, and this method of surcharging the humidified air will be found most efficacious 45 in the treatment of disease, unsanitary conditions, or unpleasant olfactory environment, &c.

All this is accomplished without interfering with the use of my device as an ordinary air vent for the radiator; and the device, in whole or in part, is adapted for permanent incorporation with a radiator as fitted for the market, or as an attachment to radiators already installed and in use. 50

55

What I claim as my invention and desire to secure by Letters Patent is,

1. A humidifying attachment for radiators, comprising a casing with means for attachment to the air vent of a radiator, 60 a pipe leading from said casing, an absorbent medium supported by said pipe and arranged to be moistened by the fluids issuing therefrom and exposed to the atmosphere and to the heat from the radiator and so 65 formed as to offer substantially no resistance to the fluids issuing from said pipe.

2. A humidifying attachment for radiators, comprising a casing with means for attachment to the air vent of a radiator, 70 a pipe leading from said casing, an absorbent medium supported by said pipe and arranged to be moistened by the fluids issuing therefrom and exposed to the atmosphere and to the heat from the radiator and so 75 formed as to offer substantially no resistance to the fluids issuing from said pipe, and a reservoir for volatile material communicating with said pipe between said absorbent medium and the end of the pipe farthest 80 from its connection with said vent.

ADDISON A. CARDWELL.
